OVAL BOWL

Marvin G. Yutzey, Moundsville, W. Va., assignor
to Fostoria Glass Company, Moundsville,
W. Va., a corporation of West Virginia

Application December 28, 1949, Serial No. 6,892

Term of patent 3½ years

(Cl. D44—10)

To all whom it may concern:

Be it known that I, Marvin G. Yutzey, a citizen of the United States of America, residing at Moundsville, in the county of Marshall and State of West Virginia, have invented a new, original, and ornamental Design for an Oval Bowl, of which the following is a specification, reference being had to the accompanying drawings, forming a part thereof, wherein:

Fig. 1 is a top plan view of an oval bowl showing my new design;

Fig. 2, a side elevational view, partially broken away to illustrate the cross sectional contour; and,

Fig. 3, an end elevational view thereof, also partially broken away to show the cross sectional contour.

I claim:

The ornamental design for an oval bowl, as shown.

MARVIN G. YUTZEY.
